UNITED STATES PATENT OFFICE.

ADOLPH WALTER, OF ATHENS, OHIO.

DIE FOR FORGING SHIFTING-RAILS.

SPECIFICATION forming part of Letters Patent No. 394,232, dated December 11, 1888.

Application filed June 8, 1888. Serial No. 276,457. (No model.)

To all whom it may concern:

Be it known that I, ADOLPH WALTER, a citizen of the United States, residing at Athens, in the county of Athens and State of Ohio, 5 have invented certain new and useful Improvements in Dies for Forging Shifting-Rails; and I do hereby declare that the following is a full, clear, and exact description of the same, reference being had to the annexed drawings, making a part of this specification, and to the letters and figures of reference marked thereon.

Figure 1 of the drawings is a perspective view of my improved die-sections, the upper 15 one of said sections being elevated to show the inner sides or faces of the section, and Fig. 2 a view showing the back rail-section in its several steps of completion.

The present invention has relation to means 20 for the manufacture of carriage or buggy shifting-rails, and it refers more particularly to the manner of producing such rails by means of suitably-constructed dies, for which a patent was granted to me November 23, 1886, 25 No. 353,100. These dies in the above-described patent were especially designed for the production of the side shifting-rail sections; and the object, therefore, of the present invention is to provide suitable dies for 30 forming the back rail-section, by which said section and the corner iron thereof is forged complete; and the invention consists in dies constructed substantially as shown in the drawings, and hereinafter described and 35 claimed.

In the accompanying drawings, A B represent the two sections of the die, between which the back section and corner iron of the shifting-rail is formed into shape, said die-sections, 40 if preferred, having suitable serrated faces, *a*, to prevent the bar of iron, when placed between the die-sections, from slipping, as in my former patent. The bar of iron, which is of suitable shape to form the back section 45 and corner iron of the shifting-rail, is taken from the furnace and placed upon that portion of the die-section B, (indicated at *b*.) said bar extending longitudinally over the face of the die-section and one end resting on the anvil *c*, and the other end of said bar resting

over and upon the serrated surface *a* of the lower section of die.

The die-section A is now brought down over the die-section B and over and upon the iron bar, and by suitable trip-hammer or other well-known means pressure is brought upon the upper die-section, which forces the metal of the bar into the depressions *d e* of the die-sections A B, respectively, and also the depression *f* of the upper one of said sections, which is at or near the corner thereof, so that when the two sections of the die are brought together the depression *f* will be in the rear of the anvil *c* to form the lug *g*, while the depressions *d e* form the lugs *h i*, respectively, as shown at C in Fig. 2. The corner of the die-section A has a depression, *l*, which joins the depression *f*, and is of form and shape to correspond with that of the anvil *c*, whereby the corner iron of the back section is produced. The bar, after 70 having been forged into shape, as shown at C, Fig. 2, is removed from the dies and again placed between them, so that they will rest between the grooves *m m'* of the die-sections A B, respectively, when they are brought together, the lug *h* resting over the grooved extension *n*, and the lug *i* resting over the grooved extension *o*, and the lug *g* resting over the grooved extension *p*, and the extension *r* of the bar resting over the grooved extension *s*, and in this position the upper die-section is brought down thereon to forge the bar into shape, as shown at D, Fig. 2, after which the bar thus shaped is again acted upon by the dies. The groove *m*, as should 85 be understood, has correspondingly-formed extensions, *n' o' p' s'*, to those of the groove *m'*. The bar, in the shape as shown at D, Fig. 2, is now taken and placed over the groove *t*, which also has grooved extensions *u v w x*, of the 90 forms shown, and correspondingly-formed groove, *t'*, with extensions *u' v' w' x'*, is provided upon the die-section A, whereby the blank D, when acted upon by the two die-sections, is forged into shape, as shown at E, 95 thereby forming the back section and corner iron of a shifting-rail complete.

In place of the lugs hereinbefore described, holes may be made through the rail, as found most desirable.

In producing the completed article the blank D is placed over the groove m' , after having been acted upon by the grooves $t\ t'$, and thence back to said grooves until the article is complete.

Having now fully described my invention, what I claim as new, and desire to secure by Letters Patent, is—

A die for forging the back sections and corner irons of shifting-rails for carriages or buggies, consisting of two die-sections having upon their faces suitable grooves and extensions thereto, depressions at their outer edges,

and at their corners an anvil and a depression of corresponding form, said anvil and depression being located at the extreme corners of the die-section and the depression joining one of the depressions which form the lug, substantially as and for the purpose set forth.

In testimony that I claim the above I have hereunto subscribed my name in the presence of two witnesses.

ADOLPH WALTER.
